PUMP

Claud F. Davis, Johnson City, Tenn.

Application October 16, 1943, Serial No. 506,470

7 Claims. (Cl. 103—121)

My invention relates to rotary hydraulic pumps of the type comprising concentric stationary and rotor elements defining a plurality of segmental cylinder spaces or working chambers separated by blades shiftable radially in the stationary element.

An important object of the invention is to construct a pump of this type for eight cycle operation per revolution with a minimum amount of fluid impulse action and with continuous uniform discharge.

A further object is to produce a pump structure in which the stationary and rotor elements define a plurality of outer and inner segmental cylinder spaces or working chambers with only one set of blades serving both the outer and the inner chambers.

A further object is to provide improved inlet and outlet porting arrangement for the outer and inner cylinder chambers and with the rotor element functioning as a valve for cooperating with the blades to control the ports for the inlet and outlet flow to and from the cylinder chambers.

Another object is to use blades in the form of cylinders or rollers, and to provide a structure in which the stationary and rotor elements are symmetrical around a common axis in order to produce perfect balance and eliminate vibration and reduce wear to a minimum.

The above enumerated and other features of my invention are embodied in the structures shown on the drawings, in which

Figure 1 is a plan view of the pump structure with the rotor housing removed;

Figure 2 is a section on plane II—II of Figure 1 with the rotor housing in place;

Figure 3 is an underside view of the rotary element;

Figure 4 is a plan view of the stationary element;

Figure 5 is a section on plane V—V of Figure 2 with the housing removed and showing the rotary element in one position; and

Figure 6 is a view similar to Figure 5 showing the rotary member rotated 90° from its position on Figure 5.

The pump structure shown is adapted to be mounted with its axis vertical, and it comprises the stationary element or base 10 having the upstanding circular flange 11 and the circular wall 12 rising therefrom concentric with the flange 11. The top side of the stationary element 10 provides the seating and bearing surface 13 for the rotary element 14. The body 15 of the rotary

element is cylindrical and seats with its bottom against the surface 13 of the stationary element concentric with the flange 11.

The body 15 of the rotary element has therein 5 the elliptical channel 16 which receives the circular wall 12 and is coaxial therewith. The channel divides the rotor body 15 into outer and inner heads 17 and 18, respectively, the outer head defining the outer elliptical surface *x* of the channel 16 and the inner head defining the inner elliptical surface *y* of the channel, the surfaces being parallel so that the channel is of uniform width throughout. The major axis of the inner head 18 fits the inner diameter of the circular wall 12 while the minor axis of the outer head 17 fits the outer diameter of the circular wall so that the inner head at the ends of its major axis engages at all times the inner side of the circular wall while the outer head at the ends of its minor axis engages at all times against the outer side of the circular wall.

The circular wall 12 has a pair of diametrically opposite radial slots 19 and 20 therethrough for the blades 21 and 22. These blades are preferably 10 in the form of cylinders or rollers whose diameter is equal to the width of the slots and the width of the channel 16, the blades being of a length to extend the full depth of the channel between the surface 13 on the stationary element 15 and the top of the channel. During operation of the structure, the circular wall 12 and the blades divide the channel 16 into four outer segmental cylinder spaces *a*, *b*, *c* and *d*, Figure 5, and four inner segmental cylinder spaces *e*, *f*, *g* and *h*, Figure 6. The cylinder spaces are of 25 90° extent and, with inlet and outlet porting arrangement to be described hereinafter, the eight cylinder spaces will sequentially have oil drawn thereto and discharged therefrom with the entire flow through the pump distributed through the eight cylinder spaces or working chambers to produce eight cycle operation.

Describing now the porting arrangement, inlet and outlet ports *i* and *o* are located respectively 30 adjacent to the outer ends of the opposite sides of the slots 19 and 20, these ports serving the outer cylinder spaces *a*, *b*, *c* and *d*. Inlet ports *i'* and *o'* adjacent to the inner ends of the opposite sides of the slots 19 and 20 serve the inner 35 cylinder spaces *e*, *f*, *g* and *h*. The location of these ports is clearly shown on Figure 4, the ports being in the stationary element 10 and terminating at their upper ends in the bearing face 13 of the stationary member which is engaged by 40 the rotor member 14. As indicated by the dotted 45 55

lines on Figure 4, and full lines on Figure 2, the inlet ports adjacent to the slots 19 and 20 are in communication with passageways 23 and 23' which extend from an inlet chamber 24 in the stationary element 10, an inlet passageway 25 through the stationary element connecting the chamber with a source of fluid such as oil. The outlet ports o and o' at the slots 19 and 20 are connected by passageways 26 and 26' with a discharge chamber 27 in the stationary element 10, this chamber being shown in Figure 2 as being above the inlet chamber 24, these chambers being concentric with the stationary element.

The stationary element 10 has in its upper side the cylindrical bearing recess 28 for receiving the bearing boss 29 on the rotor element 14. A passageway 30 extends from the discharge chamber 27 to the bottom of the bearing recess 28 for communication with the discharge bore 31 through the body 15 of the rotor element and the shaft 32 extending therefrom. This shaft may be connected with a suitable driving motor for the rotor element 14.

When the rotor element 14 is rotated, the blade cylinders 21 and 22 will be engaged by the outer and inner elliptical walls x and y of the channel 16 to be moved back and forth in the slots 19 and 20 in the circular wall 12 of the stationary element, the blade cylinders at their lower ends moving back and forth between the inlet and outlet ports i, i' and o, o', respectively. As shown on Figure 5, when the major axis of the elliptical channel 16 is in alignment with the slots 19 and 20, the blade cylinders will be at the outer ends of the slots to be interposed between the respective outer inlet and outlet ports i and o, while the inner inlet and outlet ports i' and o' will be covered by the inner elliptical head 18. As shown on Figure 6, when the minor axis of the elliptical channel 16 is in alignment with the slots 19 and 20, the blade cylinders will be at the inner ends of the slots to be interposed between the inner inlet and outlet ports i', o', while the outer inlet and outlet ports i and o will be covered by the outer head 17 of the rotor element. Thus, the outer and inner heads 17 and 18 of the rotor element will function as valves to cooperate with the blade cylinders to prevent direct connection between inlet and outlet ports and to control the ports for the proper sequential flow of fluid into the various cylinder spaces or working chambers and the outflow or discharge therefrom. With the arrangement shown, as the rotor element rotates, the fluid will be drawn in through the inlet 25 to the inlet chamber 24 and from there through the exposed inlet ports into the corresponding working chambers for discharge from these chambers through the exposed outlet ports to the outlet or discharge chamber 27 and from there upwardly through the bore 31 of the shaft 32.

The rotor element is enclosed by a cylindrical cup shape housing 33 having the shoulder 34 for seating against the flange 11, and having the flange 35 threading on to the stationary element 10. A bearing member 36 in the recess 28 receives the boss 32. A neck 37 extends up from the housing 33 to receive the shaft 32, and this neck has the inner flange 38 between which and the rotor body a bearing member 39 is interposed. When the housing 33 is applied, the rotor element will be held to the surface 13 of the stationary element 10. A lock screw 50 is provided for the housing.

When the pump is operating under heavy pres-

sure, oil may escape out between the rotor and the surface 13, and clearance space 40 is therefore provided between the rotor and the housing 33 and flange 11 into which the escaping oil may flow to exert pressure down against the rotor to counteract and balance any upward pressure and thus keep the rotor seated.

A gland nut 41 threads into the outer end of the housing neck 37 for compressing packing 42 around the shaft 32 to seal against leakage from the space 40.

On Figure 2 a passage 43 is shown extending laterally from the outlet passages 26' through the stationary element to the exterior thereof, a plug 44 closing the passage end. It may be desirable to discharge the oil from the side of the stationary element instead of upwardly through the shaft 32. In such case, the plug 44 would be withdrawn, and the outer end of the shaft would be plugged or a solid shaft would be used.

All the parts of the pump structure being coaxial and symmetrical, vibration is eliminated and perfectly balanced operation results. The blade cylinders have only line contact with the sides of their guide slots and with the elliptical surfaces of the channel 16, and are furthermore bathed at all times in oil, so that the movement of the blades is practically without friction. The bearing surface between the rotor and stationary element is also kept supplied with oil so that the friction of operation of the structure and consequential wear is reduced to a minimum. The structure comprises a minimum number of parts which are of simple shapes and can be economically manufactured and assembled.

I have disclosed a practical and efficient embodiment of my invention but I do not desire to be limited except by the appended claims to the exact construction, arrangement or operation shown and described as changes and modifications may be made without departing from the scope of the invention.

I claim as follows:

1. A pump comprising a rotor element having an outer annular member presenting an elliptical surface on its inner side and an inner elliptical member presenting an elliptical surface to the surface on said outer member to define an elliptical channel between said surfaces, a stationary element engaged by said rotor element and having a circular wall extending therefrom into said channel to divide said channel into inner and outer working chambers, said wall having radial slots therethrough, blade elements movable radially in said slots by the engagement therewith of said elliptical surfaces, and inlet and outlet passageways in said stationary element terminating adjacent to said slots in the paths of portions of said rotor members whereby said rotor members will function as valves to control the connections of said inlet and outlet passageways with said working chambers, said blade elements functioning to prevent direct connection between said inlet and outlet passageways.

2. A pump comprising two relatively rotatable elements, one of said elements having an elliptical channel therein of uniform width throughout, the other element having a circular wall thereon engaging in said channel to divide said channel into inner and outer working chambers, said wall having radial slots therethrough, inlet and outlet ports for said working chambers located in said other element adjacent to said slots, and blade members in the form of cylindrical rollers movable radially in said slots by the engage-

ment therewith of the walls of said channel and functioning to prevent direct connection between inlet and outlet ports, said inlet and outlet ports being in the paths of portions of said one element adjacent to said channel whereby said one element will function as a valve to control the connection of said ports with said working chambers during relative rotation of said elements.

3. A pump comprising relatively rotatable elements having engaging bearing surfaces, the first of said elements having an elliptical channel therein concentric therewith, the second of said elements having a circular wall engaging in said channel to divide said channel into inner and outer cylinder spaces, said wall having diametrically opposite radial slots therethrough, inlet and outlet ports in said second element for said outer cylinder spaces disposed at the opposite sides of said slots adjacent the outer ends thereof and inlet and outlet ports in said second element for said inner cylinder spaces disposed at opposite sides of said slots at the inner ends thereof, blade members in said slots extending across said channel to be radially shifted in said slots upon relative rotation of said elements to be interposed between the inner and outer inlet and outlet ports respectively, said inlet and outlet ports being in the paths of portions of said first element to be sequentially opened and closed thereby, whereby said first element will function as a valve to control the sequential connection of said ports with said cylinder spaces.

4. A pump comprising a stationary element having a bearing surface, a rotor element seating on said bearing surface for rotation thereon, said rotor element having an elliptical channel therein of equal width throughout with its axis coincident with the rotation axis, said stationary element having a circular wall projecting therefrom into said channel concentric with the rotation axis, said wall having two diametrically opposed radial slots therethrough, blades in said slots extending across said channel to be shifted radially in said slots by the elliptical surfaces of said channel when said rotor element is rotated, said wall and said blades during rotation of the rotor element dividing said channel into inner and outer cylinder chambers, inlet and outlet passageways in said stationary element, inlet and outlet ports extending from said passageways and terminating in said bearing surface inside of said wall adjacent to the inner ends of said slots for connection with the inner cylinder chambers, and inlet and outlet ports extending from said passageways and terminating in said bearing surface outside of said wall adjacent to the outer ends of said slots for connection with the outer cylinder chambers, said blades functioning to prevent direct communication between inlet and outlet ports, said inlet and outlet ports being in the paths of portions of said rotor element whereby said rotor element will function as a valve to control the sequential connection of said inlet and

outlet ports with the inner and outer cylinder spaces.

5. A pump comprising a stationary element having a flat bearing surface, a rotor element seating on said bearing surface for rotation thereon, said rotor element comprising inner and outer elliptical portions spaced radially to define therebetween an elliptical channel, said stationary element having a circular wall projecting from said bearing surface into said channel, said wall having slots therethrough, blades in said slots extending across said channel to be shifted radially by the elliptical surfaces of said channel when said rotor element is rotated, said wall and blades dividing said channel into inner and outer hydraulic cylinder chambers, and inlet and outlet ports for said chambers all terminating in the plane of said bearing surface in the paths of said rotor element portions to be progressively overlapped by said rotor element portions, whereby said portions will function as slide valves to control the sequential connection of said ports with said cylinder chambers.

6. A pump comprising two relatively rotatable elements having bearing faces engaging in a bearing plane, one of said elements having an elliptical channel therein, the other element having a circular wall thereon engaging in said channel and dividing said channel into inner and outer working chambers, said wall having radial slots therethrough, inlet and outlet ports for said working chambers located in said other element adjacent to said slots, and cylindrical blade members movable radially in said slots and functioning to prevent direct connection between said inlet and outlet ports, said inlet and outlet ports all terminating in said bearing plane in the paths of portions of said one element whereby said one element will function as a slide valve to control the connection of said inlet and outlet ports with said working chambers during relative rotation of said elements.

7. A pump comprising relatively rotatable concentric elements having flat bearing faces in bearing engagement with each other, one of said elements having an elliptical channel therein concentric with said element, said other element having a circular wall projecting therefrom into said channel and having radial slots, cylindrical blades in said slots for radial movement therein during relative rotation of said elements, said circular wall and said blades dividing said channel into a plurality of inner and outer hydraulic chambers, and inlet and outlet ports in said other element communicating with said channel and all terminating in the bearing face of said other element in the paths of portions of said one element, whereby, during relative rotation of said elements, said one element will function as a slide valve for said ports to control the sequential connection thereof with said inner and outer hydraulic chambers.

CLAUD F. DAVIS.
